UNITED STATES PATENT OFFICE

2,436,333

FUR FUMIGATING AND CLEANING APPARATUS

Nathan Root, Grand Rapids, Mich.

Application January 5, 1946, Serial No. 639,260

3 Claims. (Cl. 69—23)

1

This invention relates to a fur cleaning and fumigating machine and to a process for effecting such operations. More particularly, the invention relates to an apparatus and process wherein the garments are simultaneously cleaned and fumigated while the garments are tumbled in a rotating drum in the presence of cleaning materials and fumigants.

The method commonly used for cleaning fur garments consists of placing the garments loosely in a drum adapted to be slowly rotated and to cleanse the fur by the action of a mixture of sawdust impregnated with a suitable solvent or detergent material. During the rotation of the drum, the garments and sawdust are tumbled whereby the sawdust acts to carry the cleansing materials deeply into the pelts and retain the cleansing materials in intimate contact with the hairs and skins until sufficient time has elapsed for thorough cleansing to have occurred. Following the cleansing treatment, the garments must be thoroughly shaken to remove the sawdust and its impregnated detergent material.

In addition to these two separate steps, namely, the cleansing of the fur garments with sawdust followed by the separation of the sawdust from the garments, the desirable procedure involves the subjection of the furs to a third separate treatment. This involves a de-mothing treatment which heretofore has been carried out in a separate closed cabinet, wherein the garments are hung and exposed for a predetermined period of time to a fumigating gas, the gas in the cabinet being under pressure. After a suitable period of time, the gas is vented harmlessly to the atmosphere and the garments removed.

The above old established process has the disadvantage of involving three separate treating steps for cleansing and fumigating, as well as the use of separate cleansing and fumigating equipment. In my improved process and apparatus these disadvantages are eliminated by uniting the cleansing and fumigating treatment and apparatus.

Accordingly, one of the objects of my invention is to provide a process whereby garments may be simultaneously cleaned and fumigated.

Another object of my invention is to provide an apparatus in which a detergent action and fumigation can take place simultaneously.

Another object of the invention is to provide a means for thoroughly permeating fur garments at substantially atmospheric pressure with gaseous de-mothants.

2

The invention is not limited to the type of rotating drum shown and described herein. My combined cleansing and fumigating operation may be carried out in any type of closed cabinet wherein there is provided a rotatable drum suitably equipped with a means for feeding into the cabinet a gaseous fumigant, and equipped with means for expelling or exhausting the fumigant and other volatile matter from the drum at the end of the processing treatment.

Referring now to the drawing, which shows a cross-sectional view of one form of machine, for example as disclosed in the United States Letters Patent No. 2,388,619, granted to me on November 6, 1945, there is shown apparatus comprising a base 10 to which is secured by any suitable means the casing 11 having the front and rear panels 12 and 13 respectively. These panels comprise a circular portion extending downwardly into a substantially rectangular portion. Joining the panels is a peripheral wall 16 substantially cylindrical in form and extending downwardly in straight portions to correspond with the contour of the panels 12 and 13. The casing 11 is welded or otherwise suitably joined to yield a rigid cabinet.

Within the casing 11 is a drum 42, cylindrical in form, and comprising a circular rear wall 43 and an annular front wall 44, the latter having an aperture 45 flanged as at 46 to provide rigidity and a smooth entrance for access to the interior of the drum 42 through the door 64. The door 64 is provided with a finished face 67 equipped with a gasket to provide a tight seal when the door is locked. A circular door 152 is hingedly or otherwise carried on the drum wall 44 and is equipped with locking means to assure a tight seal of the aperture 45 when the door 152 is closed. The curved wall of the drum 42 is preferably provided with a plurality of rectangular openings 51 covered by a wire mesh screen 52.

Attached as by bolts 21 to the panel 13 is the housing 22 carrying an integral bracket 23 for enabling a fluid-feeding nozzle 40 to remain rigidly mounted during the drum's rotation, the inner end of the nozzle 40 being fitted into the end of the hollow shaft 38. A stuffing box 84 permits rotation of the drum with respect to the nozzle. Connected to the outer end of the nozzle 40 is a copper tube 143 receiving a gaseous fumigant from a steel cylinder 144, the contents of which are controlled by means of the cylinder valve 145.

A motor-driven blower 131 serves to remove volatiles or fumigant gas from the interior of

the drum. The intake duct 133 of the blower is connected into the top of the peripheral portion 16 of the cabinet, as shown at 134. A common type of circular swingable damper 153 in the duct 133 prevents escape of fumigant through the duct during the period when fumigation takes place. The exhaust opening 135 of the blower is open to the atmosphere. A series of louvers 150 equipped with hinged covers 151 aid in controlling the ventilation of the machine. During the time the machine is operating the covers 151 are closed. When fumigant and other volatiles are being exhausted the covers 151 are opened to allow air to enter for flushing the fumigant out of the drum, the blower 131 providing the proper suction.

Example.—In using the machine, the doors 64 and 152 are opened, the fur garments inserted through the openings in the casing and drum and deposited within the drum 42. Then a predetermined amount of the proper cleaning material, for example, wood sawdust impregnated with detergents or solvents, is sprinkled over the garments. The doors 64 and 152 are then locked to thereby provide a gas-proof seal. The drum 42 is then made to rotate by any suitable power means and simultaneously therewith a stream of fumigant gas, which may be a mixture of carbon dioxide and methyl formate, is fed into the drum 42 from the gas cylinder 144 by having the valve 145 open to allow the gas to flow through the copper tube 143 into the nozzle 40 and on through the interior of the shaft 38 into the drum. During the cleaning and fumigation doors 64 and 152 are tightly sealed and the covers 151 and damper 153 closed, thus assuring a gas tight condition within the casing 42. A sufficient amount of fumigant is admitted to thoroughly permeate the contents of the drum and is allowed to accumulate to produce a pressure slightly greater than atmospheric to assure thorough penetration of the fumigant. During this operation the fur garments and cleaning substance are tumbled together within the drum for about thirty minutes or until it is determined that the garments are properly cleaned. During this portion of the process, known in the trade as "drumming," the garments and the sawdust are retained within the drum in the necessary intimacy of contact, whereby the tumbling motion of the garments and sawdust effect an efficient cleansing action, the fragmentary particles being brought down and around the hairs in a thorough but gentle manner.

The intimate exposure of the fur garments to the sawdust and its impregnated detergent material, by means of the tumbling motion, also brings about an intimate contact of the fumigant gaseous material with the fur garments. This contact is sufficiently thorough to provide an efficient fumigating action.

After the combined cleaning and fumigating operation, the dampers 151 and 153 are opened and all noxious fumes are exhausted through the duct 133 by the blower 131.

During the combined cleaning and fumigating operation the screens 52 are closed by shutters 32 so that none of the sawdust detergent material may escape from the drum. After the desired detergent and fumigant action has been completed, the shutters 32 are opened and the rotation of the drum 42 continued until all of the sawdust material has been thoroughly shaken out of the garments and removed from the drum by sifting through the screens 52.

The closing and opening of the screens 52 may be carried out in any convenient manner. Thus, this may be accomplished by means of the shutter-leaves arrangement which is described in my patent herein referred to, or one may use other means such as providing the screens with a sliding damper arrangement.

The above example illustrates a combined cleansing and fumigating action carried out in one step in a rotating drum. The fumigating treatment, however, does not necessarily have to take place simultaneously with the detergent action. One may, if one so desires, first apply the detergent, then shake out the sawdust detergent and separate it from the fur garments in the drum and then allow the gaseous fumigant material to feed from the cylinder 144 into the drum and apply the fumigating treatment. The advantage of this separate fumigating step over the commonly used de-mothing cabinet process resides in the fact that in the present instance the inclosure of the garments within the cabinet makes it unnecessary to fumigate under pressure. The surfaces of the furs are efficiently exposed to the gaseous fumigant, thereby enabling the fumigant to penetrate all portions of the fur garment without the need of additional pressure to cause such penetration. Another advantage of carrying out the fumigation in the rotating drum is the elimination of the expense of separate fumigating equipment.

My invention may also be advantageously carried out by using a combined detergent and fumigating procedure within a completely closed, non-screened rotating drum and then transferring the cleansed, fumigated fur garment to a rotating perforate drum for the purpose of separating the sawdust detergent from the garments.

The essence of the invention resides in the provision of a means for fumigating fur garments within the same equipment used for cleansing the garments.

While I have shown a particular embodiment of my invention, it will be understood, of course, that I do not wish to be limited thereto since many modifications may be made, and I therefore contemplate by the appended claims to cover any such modifications as fall within the spirit and scope of my invention.

50 I claim:

1. A cleaning machine adapted to receive fur garments, a particulate cleaning material and a gaseous fumigant, comprising in combination a supporting structure, a hollow cylindrical drum having a hollow shaft and supported for rotation in said structure and adapted to receive the garments, cleaning material and fumigant, means for feeding gaseous fumigant from a supply cylinder to said shaft of said drum, and means for removing said fumigant from said drum.

55 2. A machine for simultaneously cleaning and fumigating fur garments including the use of a particulate cleaning material, comprising in combination a frame, a perforate hollow cylindrical drum for receiving the garments and cleaning material mounted for rotation in said frame and having a hollow shaft, the interior of said shaft being in fluid communication with the interior of said drum, a casing surrounding said drum, means for feeding gaseous fumigant from a supply cylinder to said hollow shaft, and exhaust fan means for discharging said fumigant from said drum.

60 3. A machine for simultaneously cleaning and fumigating fur garments including the use of a

particulate cleaning material, comprising in combination a frame, a perforate rotatable hollow cylindrical drum for receiving the garments and cleaning material mounted for rotation in said frame and having a hollow shaft, the interior of said shaft being in fluid communication with the interior of said drum, a casing surrounding said drum, a conduit connected at one end to said shaft and extending to a gaseous fumigant supply cylinder, means for controlling the feed of fumigant from said cylinder to said drum, and pump means for exhausting the fumigant from the drum.
